(57) **CLAIM**

The ornamental design for a door facing, as shown and described.

DESCRIPTION

FIG. 1 is a front perspective view of a door facing;
FIG. 2 is a front elevational view;
FIG. 3 is a rear elevational view;
FIG. 4 is a top plan view;
FIG. 5 is a bottom plan view;
FIG. 6 is a cross sectional view taken along the line 6-6 of FIG. 2;
FIG. 7 is a cross-sectional view taken along the line 7-7 of FIG. 2;
FIG. 8 is an enlarged fragmentary cross-sectional view of a portion of FIG. 7;
FIG. 9 is a left side elevational view;
FIG. 10 is a right side elevational view;
FIG. 11 is a cross sectional view taken along the line 11-11 of FIG. 2;
FIG. 12 is a front perspective view of a second version of a door facing;
FIG. 13 is a front elevational view;
FIG. 14 is a rear elevational view;
FIG. 15 is a top plan view;
FIG. 16 is a bottom plan view;
FIG. 17 is a cross sectional view taken along the line 17-17 of FIG. 13;
FIG. 18 is a cross sectional view taken along the line 18-18 of FIG. 13;
FIG. 19 is an enlarged fragmentary cross sectional view of a portion of FIG. 18;

(Continued)

FIG. 20 is a left side elevational view; FIG. 21 is a right side elevational view; and, FIG. 22 is a cross sectional view taken along the line 22-22 of FIG. 13. The profiles of FIGS. 8 and 19 extend continuously about all panels of the associated door facings. The dash-dash broken lines designate unclaimed features of panels of the door facing and seams on the front of the door facing, and form no part of the claimed design. The dot-dot-dash broken lines of FIGS. 7, 8, 18, and 19 depict the limits of the enlarged views and form no part of the claimed design.

1 Claim, 12 Drawing Sheets
